UNITED STATES PATENT OFFICE.

WILLIAM A. H. ROBINSON, OF SPRINGFIELD, MASSACHUSETTS.

DESIGN FOR A FINGER RING.

Application filed November 23, 1922. Serial No. 4,370. Term of patent 14 years.

To all whom it may concern:

Be it known that I, WILLIAM A. H. ROBINSON, a citizen of the United States of America, residing at Springfield, county of Hampden, State of Massachusetts, have invented a new, original, and ornamental Design for Finger Rings, of which the following is a specification, reference being had to the accompanying drawing, forming part thereof.

The figure is a perspective view of the ring, showing my new design which comprises the alternate arrangement of a series

of two heart shaped figures showing an arrow extending therethrough and series of four lobed figures located between the opposite ends of the arrows, said figures being located only on the outer edge of the ring, and made smooth or without chasing and the spaces between the figures being chased or roughened.

What I claim is:

The ornamental design for a finger ring as shown and described.

WILLIAM A. H. ROBINSON.
